H. W. VAN LEIR.
VALVE FOR BOTTLE FILLING APPARATUS.
APPLICATION FILED MAY 7, 1912.

1,093,365.

Patented Apr. 14, 1914.

UNITED STATES PATENT OFFICE.

HENRY W. VAN LEIR, OF PHILADELPHIA, PENNSYLVANIA, ASSIGNOR, BY MESNE ASSIGNMENTS, TO S. S. WENZELL MACHINE COMPANY, OF PHILADELPHIA, PENNSYLVANIA, A CORPORATION OF PENNSYLVANIA.

VALVE FOR BOTTLE-FILLING APPARATUS.

1,093,365.

Specification of Letters Patent. Patented Apr. 14, 1914.

Application filed May 7, 1912. Serial No. 695,620.

To all whom it may concern:

Be it known that I, HENRY W. VAN LEIR, a citizen of the United States, and a resident of Philadelphia, Pennsylvania, have 5 invented certain Improvements in Valves for Bottle-Filling Apparatus, of which the following is a specification.

My invention relates to bottle filling valves of that type in which the valve slides 10 on the filling tube, and is opened by the upward pressure of the bottle or jar and closed by the action of a spring or equivalent device against a seat carried by an air vent tube which passes up through the filling 15 tube, the objects of my invention being to provide for the proper support of the air vent tube while permitting of the ready insertion and removal of the same, to insure a tight closing valve, and to provide for 20 the proper escape of the air from the interior of the bottle during the filling operation.

In the accompanying drawing Figure 1 is a vertical sectional view of a valve for 25 bottle filling apparatus constructed in accordance with my invention, the valve being shown in the closed position; Fig. 2 is a similar view showing the valve in the open position, and Fig. 3 is a perspective 30 view of the air vent tube supporting device.

In the drawing, 1 represents part of the bottom of a tank for containing the liquid with which the bottles are to be filled, said tank having a number of depending nipples such 35 as shown at 2, each of these nipples being threaded at its lower end, as shown at 3, for the reception of a coupling nut 4, whereby the flanged upper end of the filling tube 5 is firmly confined to the lower end of the 40 nipple.

Passing through the filling tube 5 is an air vent tube 6, which is supported at its upper end by means of a cage contained in the interior of the tank and comprising a 45 base ring 8 adapted to a countersunk recess 12 in the bottom 1 of the tank and having upwardly projecting legs 9 which rigidly and fixedly support a ring 10 having an opening or gap 10^a in one side, as shown in 50 Fig. 3, and having at the top a seat 11 for receiving a collar 6^a at the upper end of the vent tube 6, as shown in Figs. 1 and 2.

Secured to the lower end of the vent tube 6 is a plug 14 having a truncated coni-

cal upper face 15 and a truncated conical 55 lower face 16, and between these upper and lower faces is a seat 17 for the valve 22, the latter forming part of a tubular slide 21 which is guided so as to be free to move vertically on the filling tube 5, and is normally moved downwardly on said tube, so as to cause the valve 22 to bear upon the seat 17, by means of a coiled spring 23 or equivalent device, said coiled spring being interposed between the underside of the 60 coupling nut 4 and an annular flange 24 projecting from the tube 21 and having an outer vertical flange 25 projecting above and below the flange 24, the upper projecting portion surrounding a recess 26 which 65 receives the lower portion of the spring 23, and the lower projecting portion surrounding a recess which receives a gasket 27 of rubber or other elastic material, for sealing the mouth of the bottle or jar during the 70 filling operation. The flange 25 has a drainage opening 28 therein and the flange 24 has an opening 29 for the passage of a suitable tool whereby the gasket 27 may be dislodged 75 when desired.

The plug 14 is supported upon the lower end of the air tube 6 by outwardly flaring the lower end of said tube, as shown at 18, into the correspondingly flaring lower end of the central opening formed in the plug 85 14 for the reception of the tube 6, and in said plug, above the bottom of the latter, are formed radiating openings 19 registering with openings 20 in the tube and providing 90 passages for the inflow of air to said tube after its lower end has been sealed by the rise of the liquid in the bottle during the filling operation.

The plug 14 has, immediately above the external seat 17 thereon, an external cylindrical wall, and the valve 22 has a corresponding internal cylindrical wall immediately above its lower end which bears upon the seat 17 when the valve is closed, the internal cylindrical wall of the valve fitting 100 snugly to the external cylindrical wall of the plug 14 so as to provide an additional seating surface and thereby aid in the formation of a tight joint between the valve and the plug and correspondingly aid in preventing leakage between the two when the valve is closed.

The normal position of the parts is the

closed position represented in Fig. 1, but when a bottle is raised beneath the valve the mouth of said bottle first strikes the under face of the elastic gasket 27 and thereby seals said mouth, further upward movement of the bottle causing the lifting of the valve against the pressure of the spring 23 and thereby permitting the flow of liquid from the filling tube 5 into the bottle through the 10 annular space between the valve and its seat, as shown in Fig. 2. As the liquid enters the bottle the air can escape from the latter through the vent tube 6 until the level of liquid rises in the bottle to such 15 point as to close the vent openings 19, whereupon further rise of the liquid will trap the air in the upper portion of the bottle and will compress the same until it counter-balances the pressure of the hydrostatic 20 column of liquid in the filling tube and tank, whereupon further entrance of liquid into the bottle is arrested. As the filled bottle is lowered the valve 22 descends with the same until it is finally again seated upon 25 the plug 14, thus closing communication between the interior of the bottle and the filling tube. The collar at the upper end of the vent tube 6 and the plug at the lower end of the same are secured to said tube before the application of the same to the supporting cage, hence the provision of the side 30 opening or gap in the ring 10 so that the vent tube can be introduced from below and at an angle until the collar at the upper end 35 of said tube is above the ring 10, whereupon

the tube can be passed through said opening until it has assumed a vertical position and the collar at the upper end of the tube can be dropped into its seat 11 in the top of the ring. 40

I claim:

1. The combination, in a bottle filling apparatus, of a filling tube, a valve, an air vent tube passing through said filling tube and having at its upper end a supporting collar 45 and at its lower end a plug having a seat for the valve, a ring having a seat for said supporting collar and a side opening through which the filling tube can be passed laterally, a support for said ring and legs 50 extending downwardly from said ring to said support and serving to rigidly and fixedly mount the ring.

2. The combination of the tank having an opening therein, and a counter-sunk recess 55 surrounding said opening, a filling tube, a valve therein, an air vent tube having a seat for said valve, a support for said tube carried by said tank and having an annular base seated in said counter-sink, legs carried by 60 said base and projecting above the same, and an open-sided ring carried by said legs and having a seat in its upper face, the air tube being adapted to pass through said open side of the ring and having a collar adapted to 65 the seat therein.

HENRY W. VAN LEIR.
